United States Patent Office

Des. 195,746
Patented July 23, 1963

195,746

FILM MAGAZINE

Hubert Nerwin, Rochester, N.Y., assignor to Eastman
Kodak Company, Rochester, N.Y., a corporation of
New Jersey

Filed Dec. 11, 1962, Ser. No. 72,812

Term of patent 14 years

(Cl. D61—1)

Fig. 1

Fig. 2

Fig. 3

Fig. 5

Fig. 6

Fig. 4

Fig. 7

Fig. 8

Fig. 9

FIG. 1 is a front perspective view of a film magazine, showing my new design;

FIG. 2 is a rear perspective view thereof;

FIG. 3 is a front elevational view thereof;

FIG. 4 is a rear elevational view thereof;

FIG. 5 is an elevational view of one end thereof;

FIG. 6 is an elevational view of the other end thereof;

FIGS. 7 and 8 are elevational views of opposite sides thereof; and

FIG. 9 is a sectional view, taken substantially on line 9-9 of FIG. 3.

I claim:

The ornamental design for a film magazine, as shown.
